UNITED STATES PATENT OFFICE.

CALVIN C. FOUTS, OF MIDDLETOWN, OHIO.

TRUCK FOR HANDLING ROLLS OF BELTING AND THE LIKE.

1,322,299.

Specification of Letters Patent.

Patented Nov. 18, 1919.

Application filed May 9, 1919. Serial No. 295,957.

To all whom it may concern:

Be it known that I, CALVIN C. FOUTS, a citizen of the United States, residing at Middletown, in the county of Butler and 5 State of Ohio, have invented certain new and useful Improvements in Trucks for Handling Rolls of Belting and the like, of which the following is a specification, reference being had therein to the accompanying 10 drawing.

This invention relates to a truck for handling rolls of belting and the like. Belting ordinarily is stored and shipped in rolls which frequently contain many feet of belting and are, consequently, very heavy. The 15 belting is used or sold in relatively short lengths, and when a section of belting is to be severed from the roll it is usually necessary to remove the roll from the bin and 20 unwind the required amount of belting, sever the same, and then return the roll to the bin all of which, because of the great weight of the roll, is more or less difficult of accomplishment. Further, it is frequently 25 necessary to handle the rolls for other reasons.

The object of the present invention is to provide a device by means of which a roll of belting, or other article, may be lifted 30 and supported while it is moved from one position to another, and while the belting is being unwound therefrom.

A further object of the invention is to provide such a device which will be very 35 simple in its construction and operation; which will be of a strong, durable character; and which will be so constructed that the roll of belting can be very easily engaged and lifted thereby.

40 In the accompanying drawings Figure 1 is a side elevation of a device embodying my invention; and Fig. 2 is a perspective view of the same showing the device about to engage a roll of belting.

45 In these drawings I have illustrated one embodiment of my invention and have shown the same in the form of a truck. It will be understood, however, that while I prefer to embody the device in the form 50 of a truck, this is not an essential part of its construction, and the novel features of the device may be useful when embodied in other forms than that of a truck.

55 As here shown, the device comprises a main structure or frame consisting of two side members 1, each of which is here shown

as in the form of an inverted V. The lower ends of the arms of the two side frames are rigidly secured one to the other by means of connecting bars 2, which extend between and 60 are rigidly secured to the arms of the respective V's and the connecting bars 3 which extend between and are rigidly secured to the ends of the parallel arms of the two side frames. The side members may also, 65 if desired, be provided with vertically extending members 4, which will impart greater strength and rigidity thereto. This frame may, if desired, be mounted upon wheels or rolls and, in the present form of 70 the device, each side frame has pivotally secured thereto midway between its front and rear ends a wheel 5, which is here shown as journaled on a pin 6 carried by a bracket 7, secured to the corresponding 75 frame member 4, and a gusset plate 8, which latter also serves to reinforce the frame structure. The connecting bars 2 are provided with upwardly curved portions 9 to receive the upper portions of the wheels 80 and thus permit the lower part of the frame structure to be arranged on a level lower than the top of the wheels. These wheels form the main support for the frame, and it will be noted that the frame is pivoted on 85 the wheels in such a manner that it may be tilted to bring the forward edge of the frame in engagement with the floor when so desired. The rear portion of the frame is preferably provided with suitable supports 90 to retain the frame in a substantially horizontal position when so desired, and these supports are here shown in the form of swiveled casters 10.

Mounted on the frame is a suitable lifting 95 device having parts adapted to engage the roll of belting, or other load to be lifted, so that the latter can be lifted from its support and moved into place between the two side members of the frame. This lifting device 100 may take various forms, but it is here shown as a lever like structure comprising two parallel arms or levers 11 which are connected one to the other at their rear ends by a cross bar 12 and are pivotally mounted between their ends upon the upper portions of the respective side members of the main frame, as shown at 13. The forward ends 105 of the lever arms, which extend beyond the axis of the lever, are preferably turned at an angle to the main portions of the lever arms 110 so that when the lifting device is in its nor-

normal position, as shown in Fig. 1, the forward ends of the lever arms will extend upwardly and rearwardly. Connected with these forward ends of the lifting arms is a 5 suitable device for engaging the load. In the present construction, which is designed more particularly for handling rolls of belting, this load engaging device is shown in the form of a pair of arms 14 pivotally 10 mounted at their upper ends on the forwardly projecting portion of the lever arms, and having in their forward edges a series of notches 15 to engage the ends of a rod or roller inserted through the central opening 15 in the roll of belting. This rod may take various forms but, as here shown, it comprises a round rod 16 having loosely mounted thereon a tube 17 and having its ends square, as shown at 18. When the squared 20 ends of the rod 16 have been inserted in the notches 15 of the lifting device the rod itself will be held against rotation and the tube 17 will rotate with the roll of belting. To reinforce the lifting device and prevent 25 the same from being subjected to undue strain, I prefer that the lower portions of the lifting arms 14 be held against lateral or turning movement, and I also prefer to so control the ends of these arms that they will 30 have no free swinging movement but that when the lifting device is in its normal position the lifting arms will be held against all movement. Both of these functions are accomplished by providing fixed inclined 35 guides for the lower ends of the arms. As here shown, each arm has near its lower end a stud 19 on which is mounted a roller 20 which extends into a T-shaped slot 21 in a guide bar 22 which is rigidly secured to the 40 adjacent side member of the main frame. These guide bars are arranged at such an inclination that when the lifting device is moved about its axis the lower ends of the arms will travel along the slots of the guide 45 bars. When the lifting device is in its normal position, the walls of the slots will prevent the arms 14 from swinging about their pivotal connections to the lever arms 11. The rollers rest upon the guide bars and 50 thus relieve the lifting device of a large portion of the weight of the load when the lifting device is in its normal or elevated position. Further, these guide bars hold the lifting arms against any tendency to lateral 55 movement or to turning movement. The forward ends of the lifting arms 11 are preferably provided with a series of openings 23 so that the lifting arms may be connected thereto at different points and the amount of 60 lifting movement imparted to the load thus varied.

When a roll of belting is to be mounted on the device the latter is moved into a position in front of the roll, as shown in Fig. 65 2, the frame tilted to bring the forward edge

thereof close to the floor, and the device then moved toward the roll of belting to cause the latter to enter the space between the two side frames and to enable the notched lifting arms to be brought into engagement with the ends of the supporting rod 16. The lifting device is then moved about its axis to cause the lifting arms to move downwardly and forwardly into engagement with the rod 16. After this engagement has been effected the lifting device is moved to its normal position, thus elevating the load and moving the same rearwardly into a substantially central position with relation to the frame. The movement 75 of the lifting device to its normal position carries the forward ends of the lever arms, to which the lifting arms are connected, rearwardly beyond the vertical line of the axes of the lever arms. Thus the weight of 80 the load will tend to retain the lifting device in its normal or elevated position.

While I have shown and described one embodiment of the invention, I wish it to be understood that I do not desire to be limited 90 to the details of construction thereof as various modifications may occur to a person skilled in the art.

Having thus fully described my invention, what I claim as new and desire to secure by Letters Patent is:

1. In a device of the character described, a frame comprising side members adapted to receive a load between them, a lifting device mounted on said frame and comprising 100 a part to engage the load, and means for guiding said load engaging part of said lifting device rearwardly relatively to said side members when said lifting device is operated.

2. In a device of the character described, a frame comprising side members adapted to receive a load between them, a lifting device mounted on said side members and comprising a pair of arms having parts to engage a load, and inclined guides for the lower ends of said arms to cause the load to be moved upwardly and rearwardly relatively to said side members when said lifting device is actuated.

3. In a device of the character described, a frame comprising side members, a pair of lever arms pivotally mounted between their ends on the respective side members, and lifting arms connected at their upper ends with said lever arms and having means to engage the load to be lifted, said lifting arms being capable of pivotal movement relatively to said lever arms to permit the lower ends thereof to move transversely to 120 said side members as the load is lifted.

4. In a device of the character described, a frame comprising side members spaced apart to receive a load between them, lever arms pivotally mounted between their ends 130

- on the respective side members, and lifting arms pivotally mounted at their upper ends on said lever arms to move the load upwardly and rearwardly relatively to said side members when said lever arms are actuated, and having notches in their forward edges to receive a load supporting rod.
5. In a device of the character described, a frame comprising side members spaced apart 10 to receive a load between them, lever arms pivotally mounted between their ends on the respective side members, lifting arms pivotally mounted on the respective lever arms and having load engaging parts, and means 15 to guide the lower ends of said lifting arms transversely to said side members when said lever arms are moved about their axes.
6. In a device of the character described, a frame comprising side members spaced apart 20 to receive a load between them, lever arms pivotally mounted between their ends on the respective side members, and lifting arms pivotally mounted on the respective lever arms to permit the lower ends to 25 move upwardly and rearwardly relatively to said side members when said lever arms are actuated.
7. In a device of the character described, a frame comprising side members spaced apart 30 to receive a load between them, lever arms pivotally mounted between their ends on the respective side members, lifting arms pivotally mounted on the respective lever arms to permit their lower ends to move 35 upwardly and rearwardly when said lever arms are actuated and having load engaging parts, and means to guide said lifting arms in said upward and rearward movement and to hold the same against movement about their axes when said lever arms are stationary.
8. In a device of the character described, a frame comprising side members spaced apart 40 to receive a load between them, lever arms pivotally mounted between their ends on the respective side members, lifting arms pivotally mounted on the respective lever arms to permit their lower ends to move upwardly and rearwardly when said lever arms are actuated and having load engaging parts, and inclined guide bars carried by the respective side members adjacent to the lower ends of said lifting arms, said guide bars and said lifting arms having co-operating parts to control the movements of said lifting arms.
9. In a device of the character described, a frame comprising side members spaced apart 45 to receive a load between them, lever arms pivotally mounted between their ends on the respective side members, lifting arms pivotally mounted on the respective lever arms to permit their lower ends to move upwardly and rearwardly when said lever arms are actuated and having load engaging
- parts, inclined guide bars mounted on the respective side members of said frame and having slots therein, and studs carried by the respective lifting arms and adapted to travel in said slots.
10. In a device of the character described, a frame comprising side members spaced apart 50 to receive a load between them, a lifting device comprising lever like arms pivotally mounted between their ends on the respective side members and having their forward ends turned at an angle to the rear portions thereof, lifting arms pivotally mounted on the forward portions of the respective lever arms, said lifting device being so arranged that when in its normal or elevated position the points of connection between said lifting arms and said lever arms will lie in the rear of the axis about which said lever arms move, and means for 55 guiding said lifting arms as said lever arms are moved about their axes and for holding said lifting arms against movement about their axes when said lifting device is in its elevated position.
11. In a device of the character described, supporting wheels, a frame tiltably mounted on the said wheels and comprising side members spaced apart to receive a load between them, a lifting device pivotally mounted on said frame and comprising lifting arms arranged to be brought into engagement with the load when the frame is tilted and moved toward the load which is to be lifted, so as to cause the side members 60 of said frame to project on opposite sides of said load, said lifting device being so arranged that it will cause said lifting arms to move transversely to said frame as the load is lifted.
12. In a device of the character described, supporting wheels, a frame tiltably mounted on said wheels and comprising side members spaced apart to receive a load between them, a lifting device pivotally mounted on 65 said frame upon an axis arranged substantially in the vertical plane of the axes of said wheels when said frame is in its normal position, and comprising lifting arms arranged to be moved into positions in front of said vertical plane to receive a load and to be moved substantially into said vertical plane when said load is elevated.
13. In a device of the character described, a frame comprising side members spaced apart 70 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
14. In a device of the character described, a frame comprising side members spaced apart 75 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
15. In a device of the character described, a frame comprising side members spaced apart 80 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
16. In a device of the character described, a frame comprising side members spaced apart 85 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
17. In a device of the character described, a frame comprising side members spaced apart 90 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
18. In a device of the character described, a frame comprising side members spaced apart 95 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
19. In a device of the character described, a frame comprising side members spaced apart 100 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
20. In a device of the character described, a frame comprising side members spaced apart 105 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
21. In a device of the character described, a frame comprising side members spaced apart 110 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
22. In a device of the character described, a frame comprising side members spaced apart 115 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
23. In a device of the character described, a frame comprising side members spaced apart 120 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.
24. In a device of the character described, a frame comprising side members spaced apart 125 to receive a load between them, a lifting device comprising lever arms pivotally mounted on the respective side members of said frame, and lifting arms adjustably connected with the respective lever arms and having parts adapted to engage the load, said lifting device being so arranged that the lower ends of said lifting arms will be moved transversely to said frame as the load is lifted.

14. In a device of the character described, a frame, a lifting device comprising a structure pivotally mounted on said frame, lifting arms carried by said structure, having parts to engage the load to be lifted and capable of rearward movement relatively to said frame when said lifting device is actuated, and guides for said lifting arms.
- 5 15. In a device of the character described, arms being so arranged with relation to said structure that the load will be moved rearwardly relatively to said frame when said lifting device is actuated to lift the load.

- 10 15. In a device of the character described,

a frame, a lifting device comprising a structure pivotally mounted on said frame, lifting arms carried by said structure, having parts to engage the load to be lifted and capable of rearward movement relatively to 15 said frame when said lifting device is actuated, and guides for said lifting arms.

In testimony wherof I affix my signature hereto.

CALVIN C. FOUTS.
